UNITED STATES PATENT OFFICE.

GEORGE W. LAKE, OF RUMFORD, RHODE ISLAND, ASSIGNOR OF ONE-HALF TO FRANK W. SMITH, OF PROVIDENCE, RHODE ISLAND.

PROJECTILE-LOADING APPARATUS.

1,231,388.

Specification of Letters Patent. Patented June 26, 1917.

Application filed December 30, 1916. Serial No. 139,773.

To all whom it may concern:

Be it known that I, GEORGE W. LAKE, a citizen of the United States, and resident of the town of Rumford, in the county of Providence and State of Rhode Island, have invented certain new and useful Improvements in Projectile-Loading Apparatus, of which the following is a specification.

This invention relates to apparatus for loading projectiles, more particularly those of the larger sizes, with high explosives, and the invention has for one of its objects to provide means for forcing the charge into a heated shell, and to cool the shell while the charge and its surplus of loading material remains under the loading pressure, whereby this surplus is forced into the shell to compensate for the shrinkage or contraction of the material while cooling, thus insuring an absolutely solid charge of uniform density without pores or air spaces therein, as it is found in practice that uneven loading will throw the shell out of balance, rendering the shot inaccurate and in most cases ineffective.

A further object of the invention is to provide means whereby the cooling medium is caused to begin the cooling operation at the bottom of the shell and then work upward so as to permit the surplus filling, which may be either in granular, plastic or liquid form to be forced in at the top to compensate for the shrinkage thereby insuring a complete filling of the shell.

A still further object of the invention is to provide means for locking together the shell support, and the power applying mechanism during the shell filling operation.

The invention further consists in the provision of means for removing the power applying mechanism from alinement with the shell support, whereby the loaded shell may be readily removed and another shell positioned to be filled.

A still further object of this invention is to provide an elongated neck portion which is connected to the shell and in which a surplus portion of the charge is stored and adapted to be forced into the shell to compensate for shrinkage when the charge is

melted or liquefied, and also when it is cooled and solidified.

A still further object of the invention is the provision of means whereby the application of pressure to the charge is controlled from a point remote from the shell thereby reducing to the minimum the hazard of loading shells with high explosives.

By the employment of my improved apparatus for loading the larger size shells, a number of important advantages are obtained. Among others being, first, by first liquefying and then solidifying the charge while under pressure an absolutely perfect charge of uniform density with no pores or air holes is obtained; second, one man can operate this machine to load a shell complete in but a few minutes thus greatly increasing the production over present methods; third, by operating the loading mechanism from a distance, the danger of loading is reduced to the minimum.

With these and other objects in view, the invention consists of certain novel features of construction, as will be more fully described, and particularly pointed out in the appended claims.

In the accompanying drawings:

Figure 1— is a front elevation showing my improved loading apparatus as located in the mouth of the loading pit.

Fig. 2— is a sectional side elevation of the pit showing my loading apparatus positioned therein; and the means whereby the loading operation is controlled from behind a bulkhead at a safe distance from the loading apparatus while the same is under action.

Fig. 3— is a sectional plan view through the bulkhead or pit backing; also showing the arrangement of the pipes controlling the operation of the loading mechanism.

Fig. 4— is a sectional elevation showing the shell loading mechanism in section and illustrating the piston as forcing the charge into the shell which latter is immersed in a heat controlling medium.

Fig. 5— is a plan view of reduced size showing a section on line 5—5 of Fig. 4.

through the cylinder and showing the shape of the securing yoke.

Fig. 6— is a perspective view showing a portion of one of the tie rods and its head 5 which fits into the T slot in the base plate.

Fig. 7— is an edge view of the base plate showing the T slot therein.

Fig. 8— is a side elevation of the funnel by means of which the filling material is 10 first conducted through the filling neck into the shell.

Fig. 9— is a sectional view of the valve for controlling the pressure to and discharge from the operating cylinder.

15 In my improved method for filling large shells or projectiles with high explosives, I use a material which may be obtained commercially in granular or powdered form, or in a liquid or semi-plastic state, but for 20 convenience in handling, I preferably employ the granular form of material.

My improved apparatus consists essentially of a base plate 10 having T-shaped slots 11 and 12 in its side edges in which fit 25 the heads 13 of the tie rods or bolts 14. On this base plate is supported a water tank or receptacle 15 which is provided with a pipe 16 near its lower end for admitting hot water thereto, and a pipe 17 also near the 30 bottom of the tank for admitting cold water thereto.

This tank is provided near its top with an 35 overflow 18 for conducting away the water when it rises to a predetermined level there- 40 in. A large discharge pipe 19 having a valve 20 is connected to the bottom of the tank for quickly emptying the same after each shell loading operation. This tank is of proper dimensions to receive the desired size of shell 21 to be loaded.

In this particular instance, I have shown the pointed end 22 of the shell as provided with an opening into which the supply neck 23 is screwed, but the base 24 of this shell is 45 in some cases supplied with an opening through which the filling is passed instead of through the nose as herein shown.

A feature of this invention is the provision of the elongated supply neck 23 which 50 has a screw threaded boss 25 at its lower end, said boss being provided with an enlarged filling opening 26 and a small vent opening 27 through which the air from the shell is discharged by way of the pipe 28 55 and valve 29. This supply neck is also provided with an elongated central chamber 30 for storing an extra quantity of the filling material, over and above that poured into the shell, to be forced into the shell and 60 compensate for the shrinkage therein due to the melting of the grains and contraction due to the cooling of the charge.

This neck is provided with a U-shaped

packing 31 to form a tight joint about the plunger 32, which passes therethrough to 65 exert a pressure on the charge while first liquefying and then solidifying the same.

This piston rod or plunger extends upward through the packing 37 in the yoke 33, through the cylinder 34 and out through 70 the packing box 35 at the upper end thereof and to it is connected the piston 36 which is designed to move in this cylinder 34 to cause the plunger to exert pressure on the charge.

Any suitable medium may be employed for acting on this piston, but I preferably employ water under pressure, which is admitted thereto through the pipe 38, which pipe extends back through the bulkhead 39 80 and is provided with a pressure gage 40 and a valve 41, whereby the operator at the rear may admit pressure to the cylinder and observe by the gage the amount of pressure applied.

85 The yoke 33 is tied to the base 10 by means of the tie rods or bolts 14 so as to render effective the force of the piston upon the charge.

The operation of loading the shells or 90 projectiles with high explosives by my improved process is performed as follows:—

First a number of the shells are pre-heated in the oven 52 shown in Figs. 1 and 3 and one of these heated shells is removed and 95 the supply neck 23 is screwed thereinto. This shell thus equipped is engaged by the chain hoist 48 and lifted over into the empty tank 15, from above which the cylinder 34 has been previously removed by its individual hoist 44. The funnel 49, shown in 100 Fig. 8, is now placed in the supply neck, and the explosive material in granular form is poured through the funnel down into the shell until the same is filled and the supply neck is also filled up to the packing 31 and 105 the funnel is then removed. The material may be poured into the shell after being taken from the oven and before it is positioned in the tank if desired.

110 The chain hoist 48 is now rolled back out of the way and the cylinder 34 with its yoke 33 is positioned to rest upon the collars 50 of the rods 14, the nuts 42 are then applied securely binding the cylinder to the base, 115 and the hook 43 is disconnected from the eye 45 at the end of the plunger 32.

The operator now closes the discharge valve 20 leading from the tank, he then leaves the loading pit and passes around 120 back of the bulkhead 39. Here he first opens valve 51 permitting the hot water to flow through pipe 16 and fill the tank, thereby melting and liquefying the charge in the shell. He then operates the three-way valve 125 41 to permit the water pressure to flow

through pipe 38 into the cylinder 34 thereby driving down its piston 36 and causing the plunger 32 to enter the supply neck 23 and exert a pressure upon the charge therein, 5 forcing as much thereof into the shell as is necessary to compensate for the shrinkage of the material in changing from a granular to a liquid state. After heat and pressure have been applied to the shell for a predetermined length of time, the valve 51 is closed and valve 52 is opened permitting the cold water to enter at the bottom of the tank 15, thereby forcing the hot water out through the overflow 18 and acting upon the 10 shell and its contents to cool the same at its bottom first, and then gradually upward to its top.

The cooling action upon this plastic or liquid material in the shell at once serves to 20 harden the same into a solid mass. During this hardening process the mass is bound to shrink somewhat reducing the bulk slightly, which reduction is at once compensated for by the force of the piston acting 25 upon the charge so that when the filling operation is finished the charge in the shell is absolutely a solid mass of uniform density without any possibility of a blow hole or air space being formed therein, which is of 30 utmost importance to the successful loading of an explosive projectile.

After the shell has been completely filled and its filling material hardened by cooling, which takes a predetermined number of 35 minutes to accomplish, the operator back of the bulkhead now shuts off his supply of cold water to the tank, and the pressure to the cylinder 34, and opens the discharge therefrom, after which he enters the pit and 40 opens the valve 20, permitting the cold water to be quickly discharged from the tank 15. During this time he unscrews the nuts 42 from the bolts 14 and attaches the chain hoist to the end of the plunger 32. 45 Then by setting up this hoist he first raises the plunger withdrawing it from the supply neck 23, which action also forces the water from the upper end of the cylinder 34 out through the pipe 38 through which 50 it entered, which action is made possible by the employment of the three-way valve 41, see Fig. 9, which is connected to this pipe 38. The coupling 54 on the pipe 38 is now broken and the yoke and cylinder are 55 lifted from the rods and the same is then moved to one side by means of the carriage 47.

A fresh shell is now engaged by the chain hoist 48 and the loading operation is repeated as described.

I have described my apparatus more particularly as using the charging material in granular form, but this material may be

used in a liquid, plastic or other convenient form if desired. I have also described the 65 means whereby the shell is heated during the time the material is being forced thereinto, but in some cases it may be found that by simply heating the shell to a predetermined temperature just prior to the filling, 70 and before the application of pressure thereto will sufficiently liquefy the charge to permit the pressure to satisfactorily act upon the same.

If it is desired to use the material in a 75 liquid or plastic form instead of in a dry or granular form, I attach a pipe or hose to the inlet pipe 55 illustrated in dotted lines in Fig. 4 and force the liquid material into the neck therethrough by a pump or other 80 means. After the shell has become filled and before the pressure is applied, I close the valve 56 to prevent the liquid from being forced out therethrough when the plunger 85 32 descends.

Having thus described one illustrative embodiment of my invention, I desire it to be understood that although specific terms are employed, they are used in a generic sense and not for the purpose of limitation. I 90 therefore desire it to be understood that I reserve the privilege of resorting to all mechanical changes to which the device is susceptible, the scope of the invention being defined by the appended claims.

I claim:

1. In a shell loading apparatus, means for heating the shell, means for forcing the explosive material into the shell while heated, and means for applying a cooling medium 100 to the shell while the contents are under pressure.

2. An improved method of loading shells with explosives consisting of heating the shell, forcing the explosive material into the 105 shell while heated, and applying a cooling medium to the shell while the contents are under pressure.

3. An improved method of loading shells with explosives consisting of heating the 110 shell, forcing the explosive material into the shell while heated, and permitting the shell to cool while its contents are still under pressure.

4. In a shell loading apparatus, means for applying heat to the shell during a portion only of the filling operation, means for forcing the explosive material into the shell, and subsequently permitting the shell to cool.

5. An improved method of loading shells 120 with explosives consisting of applying heat to the shell during a portion only of the filling operation, and subsequently permitting said shell to cool, and forcing the explosive material into the shell during such heating 125 and cooling operations.

6. In a shell loading apparatus, means for forcing the explosive material into the shell, and means for both heating and cooling the shell during such filling operation.
- 5 7. In an apparatus for applying explosives to shells, means for forcing the charge into the shell, and means for alternately applying hot and cold water to the shell while being loaded.
- 10 8. In a shell loading apparatus, means for heating the shell, means for applying pressure to force the explosive material into the heated shell, and means for subsequently cooling the shell beginning at the end opposite to that through which the charge is being forced.
9. In a shell loading apparatus, means for heating the shell, means for applying pressure to force the explosive material into the heated shell, and means for subsequently cooling the shell during a portion of the filling operation beginning at the end opposite to that through which the charge is being forced.
- 20 10. In a shell loading apparatus, means for heating the shell, a pressure plunger for forcing the explosive into the shell while heated, and means for cooling the shell while the contents are still under pressure.
- 30 11. A shell loading apparatus comprising a casing in which the shell to be loaded is placed, a pressure operated plunger for forcing the charge into said shell, means for admitting a heating and cooling medium alternately to said casing to heat the shell before the charge is admitted and to cool the same while the charge is still under pressure.
12. In a shell loading apparatus, means for heating the shell, a pressure plunger for forcing the explosive into the shell while heated, means for cooling the shell while its contents are still under pressure, and means for carrying an extra supply of filling material under pressure to be forced into the shell to compensate for the contracting and shrinkage of the charge.
- 40 13. In a shell loading apparatus, means for heating the shell, a pressure plunger for forcing the explosive into the shell while heated, and a supply neck connected to the shell in which is stored the filling material under pressure of said plunger to be forced
- into the shell to compensate for the shrinkage of the charge, and means for cooling the shell while its contents and supply are still under pressure.
14. In a shell loading apparatus, a power-operated plunger for forcing the charge into the shell, a shell support, and bars for detachably securing together the power applying mechanism and said shell support said bars being laterally removable therefrom.
15. In a shell loading apparatus, a shell support, a power operated plunger for forcing the charge into the shell, means for detachably securing together the power applying mechanism and said shell support, and means for removing the power applying mechanism from alignment with the shell support.
16. In a shell loading apparatus, means for heating the shell, means for forcing the explosive into the shell while heated, and means for controlling said forcing means from a point remote from the shell.
17. In an apparatus for applying explosives to shells, means for forcing the charge into the shell, and means for alternately heating and cooling the shell while being loaded, and means for controlling the temperature of the shell from a point remote therefrom.
18. In a shell loading apparatus, means for heating the shell, a pressure plunger for forcing the explosive into the shell while heated, means for cooling the shell while the supply thereto is still under pressure, and means for controlling said pressure plunger from a point remote from the shell.
19. In a shell loading apparatus, means for heating the shell, means for applying pressure to force the explosive material into the heated shell, means for subsequently cooling the shell beginning at the end opposite to that through which the charge is being forced, and means for controlling the operating mechanism from a point remote from the shell during the pressure applying operation.
- In testimony whereof I affix my signature in presence of a witness.
